MITTEN HANGER

Marvis C. Terry, 409 N. Reuter St., Arlington Heights, Ill.

Filed May 3, 1963, Ser. No. 74,738

Term of patent 14 years

(Cl. D80—8)

FIG. 1 is a front elevational view of a mitten hanger, showing my new design;

FIG. 2 is a side elevational view thereof;

FIG. 3 is a fragmentary detail view taken on line 3—3 of FIG. 1.

The back of the mitten hanger is substantially plain. The drawing is lined for color, as shown in FIG. 1.

I claim:

The ornamental design for a mitten hanger, as shown and described.
